FRANKLIN G. HIRST, OF PHILADELPHIA, PENNSYLVANIA, ASSIGNOR TO FRANKLIN
BRASS MANUFACTURING COMPANY, OF PHILADELPHIA, PENNSYLVANIA, A COR-
PORATION OF PENNSYLVANIA.

AUTOMATIC COMPRESSION STOP AND WASTE COCK OR VALVE.

1,147,399.

Specification of Letters Patent. Patented July 20, 1915.

Application filed January 22, 1915. Serial No. 3,665.

To all whom it may concern:

Be it known that I, FRANKLIN G. HIRST, a citizen of the United States, residing in the city and county of Philadelphia, State of Pennsylvania, have invented a new and useful Automatic Compression Stop and Waste Cock or Valve, of which the following is a specification.

My invention relates to a compression and waste cock or valve, in which provision is made for closing and opening the means for the escape of the waste water remaining in the cock and its connecting pipe or conduit, and consists of a supplemental valve to control the exhaust passage and adapted to seat within the casing and on the seat around the exhaust passage upon a flange, which seat and flange are in the same plane to form a continuous bearing surface for the supplemental valve.

It further consists of other novel features of construction, all as will be hereinafter fully set forth.

For the purpose of illustrating my invention I have shown in the accompanying drawings one form thereof which is at present preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

Figures 1, 2 and 3 are vertical sectional views of a compression and waste cock embodying my invention, certain members thereof being in different positions in the different figures. Fig. 4 is a top or plan view of a casing or shell of the cock. Fig. 5 is a vertical sectional view thereof. Fig. 6 is a bottom plan view of a thimble employed, serving as the supplemental valve. Fig. 7 is a side elevation thereof. Fig. 8 is a sectional view on the line $x-x$ Fig. 7. Fig. 9 is a sectional view through the valve proper and a portion of the stem.

Similar numerals of reference indicate corresponding parts in the figures.

Referring to the drawings, 1 designates a casing or shell of the cock or valve having the inlet opening 2 and outlet 3 with the

partition 4 having a port or passage 5 therein, around which is the valve seat 6.

55

7 designates a valve which is adapted to control the port 5 and which is in suitable connection with the stem 8, in order that independent rotary movement between these parts is permitted. As here shown, I have provided a neck 9 upon the valve 7, which is engaged by a suitably shaped rib 10 on the stem 8, whereby it will be understood that the said valve will be raised and lowered with the stem, but that when the valve 7 is in engagement with the seat 6, the stem 8 may be independently rotated without imparting rotary movement to the valve, whereby injury to the valve will be prevented.

70

Projecting at a suitable point within the casing 1 above the valve seat 6 is an imperforate flange 11 and at suitable points within the casing 1 are the bosses 12, the upper face of each of which is situated in the same plane with the upper face of the flange 11 to form an even and continuous bearing surface therewith around the interior of the casing and each of said bosses is provided with a passage 13, the inner ends of which communicate with the interior of the casing above the flange and the outer ends of which open exterior of the casing 1, it being understood that the upper face of such boss serves as a seat around the passage therein.

75

14 designates recesses in the flange 11 on opposite sides of the bosses 12 and extending a suitable distance upon each side of the opening to the passage therein, as will be understood from Fig. 4.

80

15 designates a supplemental valve here shown as a thimble which is adapted for threaded engagement with the stem 8, and which is movable in the opening formed by the inner edge of the flange 11. The valve 15 is provided with ribs 16 movable in the recesses 14 in said flange 11, whereby it will be understood that the thimble is adapted for vertical movement but is prevented from rotation.

85

17 designates a shoulder on the thimble 15, serving as the seat face thereof and adapted to seat upon the flange 11 and the upper ends of the bosses 12, in order to control the passages 13 therein and by reason

105

adapted to abut the bonnet when the valve is entirely opened, whereby the supplemental valve is firmly pressed against the flange and passage seat, and a resilient device bearing on said supplemental valve to normally press and hold the same upon said flange.

2. In a device of the character stated, a casing, a valve proper for controlling the passage through the casing, a seat for said valve, a stem suitably carrying said valve, a flange in said casing above said valve seat, a boss in said casing having a passage therethrough to the exterior of the casing, the upper face of said boss forming a seat around said passage situated in the same plane with the upper face of the flange to form a continuous bearing surface therewith, recesses in said flange on opposite sides of said boss, a supplemental valve in threaded engagement with the stem and having a shoulder adapted to seat upon said flange and passage-seat, to control said passage, ribs on said supplemental valve movable in said recesses and with their ends spaced from the shoulder thereof, a packing for said supplemental valve to remove the packing from the seat around the passage, and a resilient device bearing on said supplemental valve to normally press and hold the same upon said flange.
3. In a device of the character stated, a

casing, a valve proper for controlling the passage through the casing, a seat for said valve, a stem suitably mounted, a connection between said valve and the stem for permitting an independent rotary movement therebetween, an imperforate flange within said casing above said valve seat, a boss in said casing having a passage therethrough to the exterior of the casing, the upper face of said boss forming a seat around said passage situated in the same plane with the upper face of the flange to form a continuous bearing surface therewith, recesses in said flange on opposite sides of said boss, a supplemental valve in threaded engagement with the stem and having a shoulder adapted to seat upon said flange and passage-seat, to control said passage, ribs on said supplemental valve movable in said recesses and with their ends spaced from the shoulder thereof, a packing for said supplemental valve to insure movement thereof with said supplemental valve, and a resilient device bearing on said supplemental valve to normally press and hold the same upon the flange.

FRANKLIN G. HIRST.
